PHILANDER MACY, OF ROCHESTER, NEW YORK.

Letters Patent No. 80,644, dated August 4, 1868.

IMPROVEMENT IN VALVE-ARRANGEMENT.

The Schedule referred to in these Letters Patent and making part of the same.

TO ALL WHOM IT MAY CONCERN:

Be it known that I, PHILANDER MACY, of Rochester, in the county of Monroe, and State of New York, have invented certain new and useful Improvements in Valve-Arrangements for steam and other engines; and I do hereby declare that the following is a full and exact description thereof, reference being had to the accompanying drawings, making part of this specification.

Figure 1 is a longitudinal sectional elevation of my improved arrangement.

Figure 2, a perspective view of the valve detached.

Like letters of reference indicate corresponding parts in both figures.

My invention consists in a slide-valve so arranged as to avoid in a great degree the pressure of the steam, and operating to open and close the ports by the direct action of the piston-head itself, without the use of eccentrics or other attachments, which are ordinarily employed.

It also consists in a lever-and-spring arrangement for reversing the engine while under motion, and a turning-hook for attaching to the valve to move it in any desired position.

In the drawings, A indicates the cylinder of a steam-engine; B, the piston-head working therein; C, the piston-rod; D, the pitman; E, the crank, and G the balance-wheel. These parts do not differ essentially from the corresponding ones in ordinary use.

On top the cylinder is bolted a plate, H, holding the induction-valve I, which admits the steam to the cylinder through space *a* and ports *b b*. The exhaust is carried off through passages *c c*.

Beneath the plate H rests a slide-valve, K, which shifts alternately to cover the ports. The central portion of this valve, resting under space *a*, is made open, as shown at *d*, fig. 2, and the ends *ff* thereof rest and slide closely under ribs *gg* of said plate, to cut off the escape of steam from space *a*, except through the ports, as before stated.

The ends of the valve are provided with downwardly-projecting lugs *h h*, which pass through the ports, and extend through sufficiently to be struck by bearings *ii*, secured on opposite sides of the piston-head, so that at each stroke the said valve will be made to cover and uncover the ports by this action alone.

At the extremity of the strokes, the lugs strike into notches *b' b'* of the ports, in order to give the full movement, and these notches are covered by offsets *kk*, at the ends of the valve, as clearly represented in fig. 2.

By arranging the valve as above described, and operating it by the positive action of the piston-head itself, without auxiliary parts, I dispense with the ordinary eccentrics, connecting-rods, and other devices that have heretofore been employed to operate the valve, and reduce the arrangement to the simplest form. The construction is so simple, and the parts are so few, that it is not liable to derangement of any kind.

The making of the opening *d* in the valve removes the great pressure of steam from its surface, and thus renders it capable of easy action under all circumstances. Were the full pressure upon the valve, it might be difficult to operate it easily by the piston-head without breaking the lugs *h h*; as it is, no difficulty can occur from this source.

A lever, L, is pivoted at *l* to the head of the cylinder, having bolted thereto, at *m*, a spring, *n*, composed of one or more leaves, and extending upwards to a suitable height, as shown. With this is connected, at *o*, a rod, M, having handle *p*, and extending inward loosely through the lever and plate H, so as to rest opposite a bearing, *r*, of the end of the valve. The end of the rod is turned into a hook, *s*, and a little back of this is a collar, *t*, as clearly shown in fig. 1.

The object of this arrangement is to throw the valve, whenever it is desired to reverse the engine otherwise. The reversal is accomplished with ease and safety, while the engine is under motion—an effect, so far as I am aware, which cannot be accomplished in any other engine. To reverse, it is only necessary to press the lever inward to the position indicated in red lines, when the collar *t*, striking bearing *r*, throws the valve to the opposite position at once. While this is being accomplished, the knocking or rapping that occurs from the

rapid reciprocations of the valve is expended upon the spring *n*, and not upon the lever through which the rod *M* runs loosely.

Thus it will be seen, I can produce the reversal of the engine under full motion instantly and without danger. In other engines, the steam must be turned off before this can be accomplished.

In ordinary use, the hook *s* is turned up as in fig. 1, but when it is desired to move the valve back from its farthest position, and at any time when it is desired to obtain full control of it, the hook is turned down back of bearing *r*, which bearing, thus confined between *s* and *t*, places the valve fully under control.

What I claim as my invention, and desire to secure by Letters Patent, is—

1. The construction of the valve *K* with opening *d*, bars *f*, lugs *h*, offsets *h*, and projection *r*, as herein set forth.
2. The combination of the rod *M*, provided with the turning-hook *s* and collar *t*, and the lever *L* and spring *n* with the valve *K* and its projection *r*, operating substantially in the manner and for the purposes specified.

In witness whereof, I have hereunto signed my name in the presence of two subscribing witnesses.

PHILANDER MACY.
